LOOM FOR WEAVING DOUBLE TAPES

Elbridge R. Holmes, Worcester, Mass., assignor to
Crompton & Knowles Loom Works, Worcester,
Mass., a corporation of Massachusetts

Application December 24, 1935, Serial No. 56,023

15 Claims. (Cl. 139—20)

This invention relates to improvements in apparatus and method for weaving double tapes of the kind used for instance in the manufacture of Venetian blinds and it is an important object 5 of the invention to make improved provision for holding the crossing threads during the weaving operation.

In my Patent No. 2,025,866 I have shown a loom for weaving Venetian blind tapes wherein the cross threads are advanced with respect to the fells of the two webs by a rod mounted on the lay and controlled to move to a position where it can move the cross warps forwardly at periodic intervals. The advancer rod moves backwardly 15 with the lay and as a result there is likelihood that the filling threads will not hold the crossing warps tightly enough as the lay recedes from its foremost position. This is more likely to be true where the tension of the crossing warps is relatively high, and results in an unevenness of length 20 in the cross threads.

It is an important object of my present invention to provide means for holding the crossing warps under tension during a brief period after 25 they have been moved forwardly by the advancer rod. This result I accomplish as set forth hereinafter by mounting the crossing warp advancer on a relatively stationary part of the loom, the rearward motion of the lay having no effect on slackening the crossing warps. With 30 such a construction the advancer is held in its forward position during the several successive crossings of the warp following the beat of the loom on which the crossing warps are moved forwardly.

It is necessary to manipulate the rod so that it can be moved rearwardly along a path out of alignment with the crossing warp threads and then be moved behind and into alignment with 40 them. It is a further object of my invention to provide a carriage for the advancer slidable relatively to a fixed part of the loom, such as the breast beam, and utilize actuators carried by the lay to give said advancer a part at least of the 45 motions necessary to place the crossing warps.

It is another object of my invention to provide an improved method by which the crossing warps 50 can be controlled, the method involving a final step which maintains pressure on the crossing warp threads a sufficiently long time to permit them to be caught tightly by the ground webs. This part of the method is independent of lay motion and represents an improvement over known procedures.

55 With these and other objects in view which

will appear as the description proceeds my invention resides in the combination and arrangement of parts hereinafter described and set forth.

In the accompanying drawings, wherein a convenient embodiment of my invention is set forth, 5

Fig. 1 is a vertical section through a loom having my invention applied thereto,

Fig. 2 is a view similar to the upper left hand part of Fig. 1 on an enlarged scale, the breast beam being shown in section,

Fig. 3 is a plan view taken in the direction of arrow 3, Fig. 2, showing the slide and warp crossing advancer held in normal forward position,

Fig. 4 is a vertical section on line 4—4 of Fig. 3, 15

Fig. 5 is a vertical section on line 5—5 of Fig. 3,

Fig. 6 is a view similar to Fig. 3 but with the slide released and shown in rear position, and

Fig. 7 is a front elevation taken in the direction of arrow 7, Fig. 2.

Referring particularly to Fig. 1, I have shown a loom frame 10 having two independent warp systems W and W' for the upper and lower webs C and C', respectively, these webs being manipulated in any desired manner by harness frames H. A third system of warp threads B is provided to be divided, each half to be passed from one web to the other to provide the cross supports which hold the slots of Venetian blinds. These crossing warps are controlled by front harness frames F. 30

A lever 11 pivoted to the loom frame at 12 has a web roll 13 under which the crossing warps pass and this lever is connected at its rear end with an upright rod 14 the lower end of which is attached to a lifter arm 15 pivoted at 16 to the frame. A cam 17 moving with a ratchet 18 has a scroll surface to cooperate with a lifting shoe 19 on the arm 15. The scroll cam and ratchet move about a fixed stud 20 and on which is also mounted an actuating lever 21 having a feed pawl 22 for the ratchet. The forward part of lever 21 is attached to an upwardly extending flexible actuator cord 23 given periodic feeding motions by mechanism not set forth herein but occurring at regular intervals during the loom operation, 40 dependent upon the distance between crossings. As weaving continues the slow rotation of the cam will elevate arm 15 and in turn move the roll 13 rearwardly. At the desired beat of the loom the shoe 19 will fall from the high to the low part of the scroll cam to slacken the crossing warps and permit them to be moved forwardly. The warp feeding features of my invention are set 45 forth in order to illustrate the improvements to 50

55

be described and of themselves form no part of my present invention.

The lay 25 is mounted on a lay sword 26 moving about a rocker shaft 27 and there is provided 5 a connector 28 lying between the crank shaft 29 and the lay. In order to insure parallel motion of the lay I may employ a link 30 pivoted at its lower end about a fixed axis 31 and attached at its upper end as at 32 to an arm 33 secured 10 to and projecting rearwardly from the lay.

The lay will have a set of shuttle blocks for each web space, only one set being shown herein. A block plate 35 is secured to the rear of the lay and projects upwardly therefrom to support top 15 and bottom shuttle guide blocks 36 and 37, respectively, between which is a third guide block 38. The upper and lower shuttles S and S' move between the blocks in well-known manner customary in narrow ware looms. The loom has a 20 breast beam 40 toward which the lay and shuttles move on the forward beat of the loom and provision not shown but well understood is provided for taking the double web from the breast beam and winding it on cloth rolls. The usual 25 reed R is provided and extends across the sheds of both sets of ground warps.

The matter thus far described may be similar to the structure set forth in the aforesaid patent and of itself forms no part of my present invention, the feeding of the slackener warps and the manipulation of all of the warps by the harness frames being effective to produce the desired pattern.

In carrying my invention into effect I mount 35 a guide stand 45 on the breast beam in fixed position and provide it with a rounded cloth guide 46 over which the webs pass. A web spacing unit 47 is secured to and projects rearwardly from the stand, as shown in Figs. 2 and 4, this 40 unit comprising two substantially parallel arms 48 and 49 supporting upper and lower cross bars 50 and 51, respectively, to define a space between which the webs pass. The cross bars limit separation of the webs and by fixing a definite 45 space by which the webs can be separated make it possible for the mechanism to be described to pull off the same amount of crossing warps on all crossing beats of the loom.

A slide housing 55 has spaced parallel slots 56 50 in the vertical walls 54 thereof to receive guide rails 57 on the sides of the stand 45. An upright stud 58 secured to the slide or housing 55 has pivoted thereto a lever 59, an arm 60 attached to a tension spring 61, the forward end of which is 55 anchored with respect to the slide 55. The lever 59 has a stop shoulder 62 for abutment with an adjustment screw 63 supported by the slide, and the rear part of lever 59 extends downwardly as at 64 to support a depending actuator lug 65. A 60 crossing warp advancer 66 is adjustably secured in vertical extension 64 of lever 59 and extends rearwardly terminating in a lateral bend 67 which is the part that actually engages the crossing warps.

The stand 45 has a stud 70 on which is pivoted 65 a trigger lever 71 extending forwardly for engagement with a stop shoulder 72 on one of the walls of the slide housing 55. Integral with the lever 71 is a hub 73 in which is adjustably set 70 an actuating finger 74. A tension spring 75 is interposed between the lever 71 and a fixed part of the stand 45 and serves normally to hold the trigger 71 and 74 in the full line position shown in Fig. 3. In this position the slide is positively 75 held in forward retracted position.

Mounted on the stud 70 is a sheave 76 around which is trained a flexible actuator cable 77 one end of which is attached as at 78 to the slide, as shown in Fig. 3, while the other end is connected to a tension spring 79, the farther end of which is held by a stud 80 fastened to the breast beam. When the parts are in the full line position shown in Fig. 3 the spring 79 is stretched and exerts a constant effort tending to move the slide 55 rearwardly. The latter will be held in its retracted position on all beats of the loom except those on which the crossing warps pass each other as they extend from one web to the other.

Levers 59 and 71 are rocked by means of a control plate 85 slideable on a base 86 secured to the front of the lay, as shown particularly in Figs. 2 and 7. The base 86 is provided with two spaced guide screws 87 which pass through guide slots 88 in the plate 85, thereby determining the direction in which the slide moves in a vertical direction relatively to the lay. A tension spring 89 has the upper end thereof fixed with respect to the slide 85 and the lower end attached preferably to a structure fixed with respect to the 25 lay, such as a stud 90. Under ordinary conditions gravity will act to hold the slide plate 85 down, but I prefer to use a spring to attain greater precision in the return of the slide to normal down position. A resetting screw 91 30 adjustable back and forth in an arm 92 depending from slide housing 55 is adapted to engage an upward extension 93 on the base 86 as the lay advances to reset said housing, as will be described hereinafter.

As shown in Fig. 7 the upper right hand part of control plate 85 carries an actuating lug 91 which is normally below the actuator stud 65 when plate 85 is down, while the upper left hand part of the plate carries a second lug 92 having 40 a cam face 93 normally below finger 74. With the plate 85 down, therefore, the lay can move forwardly without disturbing stud 65 and finger 74.

A small bracket 95 depends from the lay and 45 has pivoted thereto as at 96 a lever 97 carrying a grooved roll 98. The forward end of lever 97 may be reduced as at 99 and lies under the bottom of plate 85 but over a retaining clip 100 secured in vertically adjusted position on plate 50 85, as indicated in Fig. 7. The lever 97 will normally be in its low position, being thus maintained both by gravity and the action of spring 89.

An actuator cam 105 for the roll 98 is pivoted 55 as at 106 to an upright 107 stationary with respect to the loom structure. A spring 108 interposed between the cam and the upright tends to hold the former in the position shown in Fig. 7, stop elements 109 limiting movement of the cam 105 to the right as viewed in said Fig. 7. The left hand part of cam 105 is attached to a flexible connector 110 having an intermediate tension spring 111. This connector 110 passes under a sheave 112 moving about a fixed axis 65 and extends rearwardly to rise behind a second sheave 113 also movable about a fixed axis. The connector 110 then extends upwardly to control mechanism, such as a pattern chain lever not shown but acting in timed relation with the slackening movement of cross bar 13. Under normal conditions spring 108 holds the cam 105 70 out of alignment with the roll 98.

In operation, during normal running of the loom between crossing beats for the crossing 75

warps, the advancer 66 will lie between the webs and assume a position substantially the same as that shown in Fig. 3, being thus yieldingly held by spring 61. Trigger 71 will be in locking position relatively to shoulder 72 on the slide housing, holding the latter forward, and the control slide plate 85 will be down with cam 105 out of alignment with roll 98. When an indication is given for a shifting of the crossing warps, this indication coming at a time when the lay is in relatively rear position, flexible connector 110 will be pulled in a direction to move cam 105 into vertical alignment with the roll 98, as shown in dotted lines in Fig. 7. As the lay advances the roll 98 will ride up along the rear inclined surface 120 of the cam 105 and in doing so will rock lever 97 about its center 96 in a clockwise direction as viewed in Fig. 2, thereby causing the reduced extension 99 to elevate the control plate 85 relatively to the lay. This raises lugs 91 and 92 into horizontal alignment with stud 65 and finger 74, respectively.

As the lay continues to advance engagement of lug 91 with the stud 65 will rock lever 59 from the full to the dotted line position shown in Fig. 3, thereby retracting the advancer from a position between the webs. Lever 59 rocks because of the fact that the stud 65 is offset laterally from pivot 58 in a direction at right angles to the lay motion. At about the same time the inclined surface 93 of lug 92 will move finger 74 from the full to the dotted line position of Fig. 3, thereby rocking the trigger 71 so that it moves out of holding relation with respect to the shoulder 72. Thereupon contraction of spring 79 causes the flexible cable 73 to exert a rearward force on the slide housing 55, and the latter will move toward the lay until the adjustable stop screw 81 strikes the extension 83 of the base plate 86. As the lay recedes, continued contraction of spring 79 will cause rearward motion of the slide and the latter will move from the position shown in Fig. 3 to that shown in Fig. 6.

45 During rearward lay motion engagement is maintained between the lug 91 and the actuator stud 65, thus making it possible for the advancer to move rearwardly without interference with the crossing warp threads which at this time are 50 extending from their webs of origin to the opposite web and are crossed, as suggested in Fig. 1. Rearward movement of the slide housing 55 continues until the advancer is slightly behind the point of crossing of the two sets of crossing 55 warps, after which stop lugs 125 on the slide 55 engage corresponding stops 126 on the stand 45.

As the lay continues to recede the lug 91 draws away from the center 58 and the spring 61 rocks lever 59 in a counter clockwise direction as 60 viewed in Fig. 6 from the full to the dotted line position, thereby inserting the advancer into the sheds behind the point of crossing of the crossing warps. The action of inclined surface 93 on finger 74 is temporary and operative only 65 when the lay is in extreme forward position. As soon as the lay has moved back a short distance from front center spring 75 becomes effective to move trigger 71 against the adjacent depending wall of slide 55.

70 When the lay is in its rearward position control of the cam 105 is released and spring 108 thereupon returns it to the full line position shown in Fig. 7. The dwell surface 130 of cam 105 is long enough to maintain the slide plate 85 raised until 75 after the bar 67 has been moved to the dotted po-

sition shown in Fig. 6, after which the roll 98 moves down the incline 120 and the control slide plate 85 descends to its normal lowered position.

As the lay moves forwardly after reaching back center the lugs 91 and 92 are below the positions where they can engage the corresponding elements 65 and 74, and lever 59 will therefore remain in the position shown in dotted line position in Fig. 6 as the slide 55 moves forwardly by engagement between the lay carried extension 83 10 and resetting screw 81.

During this forward motion of the slide 55 the advancer 67 will engage the crossed warps as indicated in Fig. 4 and move them forwardly a distance which is determined by the desired space 15 between the webs when in use. In order to vary this distance the advancer may be adjusted back and forth relatively to the lever 59, as suggested by the check nuts 132 shown in Fig. 2.

As the slide 55 reaches its extreme forward position with the lay pushing it the trigger 71 will first slide up along the inclined front part of shoulder 71 and then under action of spring 75 will snap down behind said shoulder to hold the slide locked in forward retracted position. The 20 slide and therefore the advancer will remain in this position after the lay leaves front center and moves rearwardly, and will remain in this position until the next crossing warp B is called. The 25 advancer is therefore able to withstand any 30 strains which may be imposed upon the crossing warps incident to shedding operations immediately following the resetting of slide 55. In this way assurance is given that the crossing warps 35 will not slip with respect to their webs and the latter will therefore be accurately and uniformly spaced when used in a Venetian blind due to the fact that all of the crossing warps are of substantially the same length.

As weaving continues the webs will advance 40 with respect to the cross bars 55 and advancer, thereby carrying the crossing warps frontwardly from the advancer, but this movement of the crossing warps away from the advancer will not occur until after said warps have been firmly 45 woven into the webs. The retention of the crossing warps is an important step in the method of their control.

From the foregoing it will be seen that I have provided mechanism for holding the crossing 50 warps in forward position during the picks immediately following a crossing operation of the loom, thereby permitting tight weaving of said warps into their respective webs and insuring uniformity of spacing of the webs when the latter are put to the use for which they are ultimately designed. It will also be seen that this result is accomplished by mounting the advancer which 55 controls the crossing warps on a part which is stationary with respect to the loom during those 60 times when it is necessary to hold the crossing warps against slippage with respect to the webs. It will further be seen that the control for the advancer is exercised through a plate vertically slidable on the lay and that advancer in responding 65 to the several controls which determine its motion moves from between the webs, then while still retracted moves rearwardly with slide 55, after which it is again inserted between the webs 70 at a point behind the crossing of the crossing warps. The advancer then remains in this position as slide 55 moves forwardly. It will be seen that the method of controlling the crossing warp threads as set forth herein has an advantage over 75 previously known methods in that the crossing

warp are held against rearward slippage relatively to the webs.

Having thus described my invention it will be seen that changes and modifications may be made 5 therein by those skilled in the art without departing from the spirit and scope of the invention and I do not wish to be limited to the details herein disclosed, but what I claim is:

1. In a double shuttle loom, means to form top 10 and bottom sheds of ground warps, a reciprocating reed to move forwardly to beat up filling in both sheds, a crossing warp to extend from one shed of ground warps to the other, means to move the crossing warps to a position in advance of 15 the reed when the latter beats up filling in the ground sheds, and a lock to hold said means in forward position when the reed moves rearwardly.

2. In a double shuttle loom operating with an upper set of ground warp threads to form a top 20 web and a lower set of ground warp threads to form a bottom web, a set of crossing warps to pass from one ground set to the other ground set, a reciprocating reed to move forwardly to beat up shots of filling lying between the ground warps, 25 means to move the crossing warps forwardly relatively to the webs, and a lock to hold said means in forward position when the reed moves rearwardly.

3. In a double shuttle loom weaving two spaced 30 webs, means to form a shed for each web, each shed meeting its web at the fell thereof, harnesses to move the crossing warps from one fell to the shed corresponding to the other fell, a reciprocating reed to move forwardly to beat filling 35 into each shed, a crossing warp advancer to move the crossing warps forwardly relatively to the falls, and lock means to hold the advancer forward between the webs and in advance of the falls when the reed moves rearwardly.

4. In a double shuttle loom operating with two sets of ground warps to form two ground sheds which meet at the falls of the latter and operating 40 with a set of crossing warps, means to move the crossing warps from one set of ground warps to the other set, a crossing warp advancer movable forwardly from a position behind the crossing warps to a position in advance of the falls, and means to lock said advancer normally in the 45 position in advance of the falls to hold said crossing warps against rearward movement.

5. In a double shuttle loom operating with an upper set of ground warp threads to form a top web and a lower set of ground warp threads to form a bottom web, a set of crossing warps to 55 pass from one ground set to the other ground set, a reed to beat up shots of filling lying between the ground warps, a crossing warp advancer normally located forwardly between the webs, mechanism to move said advancer to a position 60 behind the crossing warp threads and in advance of the reed and thereafter move said advancer to normal position between the webs, and retaining means to hold the advancer in normal forward position.

6. In a double shuttle loom, means to form top 65 and bottom sheds of ground warps, a reed to beat up filling in both sheds, a crossing warp to extend from one shed of ground warps to the other, a crossing warp advancer, a lock to hold the advancer normally at rest in forward position, mechanism effective to unlock and move the advancer rearwardly to a position behind the crossing warps and thereafter move said advancer forwardly in front of the reed to engage and move 70 the crossing warps forwardly on a given beat of

the loom, and means to cause the lock to move to locking position relatively to the advancer to maintain said advancer and crossing warps in forward position during succeeding beats of the loom.

7. In a double shuttle loom operating with an upper set of ground warp threads to form a top web and a lower set of ground warp threads to form a bottom web, a set of crossing warps to pass from one ground set to the other ground set, a reed to beat up shots of filling lying between the ground warps, a crossing warp advancer, a lock operative to retain the advancer normally in a position between the webs, and mechanism to unlock and move the advancer rearwardly from 10 normal position to a position behind the crossing warps and thereafter move the advancer forwardly in front of the reed to move the crossing warps to positions between the webs, and means thereupon effective to move the lock to holding 15 position relatively to the advancer to hold the latter and crossing warps in forward position.

8. In a double shuttle loom operating with an upper set of ground warp threads to form a top web and a lower set of ground warp threads to 20 form a bottom web, a set of crossing warps to pass from one ground set to the other ground set, a reed to beat up shots of filling lying between the ground warps, a crossing warp advanced, holding means to maintain the advancer normally stationary between the webs, and a train of mechanism operative to disable the holding means and then move said advancer rearwardly to a 25 position behind the crossing warps and in front of the reed, said train of mechanism subsequently 30 operative to move the advancer forwardly in front of the reed to move the crossing warps forwardly relatively to the webs, and means to return the holding means to holding relationship with the advancer to hold the latter in forward position 35 during succeeding beats of the loom.

9. In a double shuttle loom operating with two sets of ground warps to form two ground sheds which meet at the falls of the latter and operating 40 with a set of crossing warps, means to move the crossing warps from one set of ground warps to the other set, a crossing warp advancer, means to lock the advancer in forward position in advance of the falls, means to move the lock to unlocking position, mechanism to effect rearward movement of the advancer on a given beat of the loom and place said advancer behind the cross warps, other means to move the advancer forwardly to move the crossing warps to positions 45 in advance of the falls, and means thereafter 50 operative to cause the lock to move into holding relation with respect to said advancer.

10. In a double shuttle loom operating with two sets of ground warps to form two ground sheds which meet at the falls of the latter and operating 55 with a set of crossing warps, means to move the crossing warps from one set of ground warps to the other set, a crossing warp advancer, means to move said advancer forwardly from a position behind the crossing warps on a given beat of the loom to a position in advance of the falls, and means to hold said advancer in forward position in front of said falls during a plurality of beats of the loom subsequent to said given beat.

11. In a double shuttle loom operating with 60 two sets of ground warps to form two ground sheds which meet at the falls of the latter and operating with a set of crossing warps, means to move the crossing warps from one set of ground warps to the other set, a lay movable toward and 65

from the fells, a crossing warp advancer normally in forward position between and in advance of the fells, means to move the advancer rearwardly to a position behind the crossing warps when the lay is in a relatively rearward position, means carried by the lay thereafter effective to move the advancer forwardly to normal position, and a lock to hold said advancer in normal forward position.

12. In a double shuttle loom operating with two sets of ground warps to form two ground sheds which meet at the fells of the latter and operating with a set of crossing warps, means to move the crossing warps from one set of ground warps to the other set, a crossing warp advancer, a lock to hold said advancer normally between and in advance of the fells, a lay, means operative on a given beat of the loom to move the advancer rearwardly to a position behind the crossing warps, and means carried by the lay and operative on said given beat of the loom to move said advancer forwardly into holding relation with said lock, the latter retaining the advancer and crossing warps in forward position during 25 beats of the loom subsequent to said given beat.

13. In a double shuttle loom operating with two sets of ground warps to form two ground sheds which meet at the fells of the latter and operating with a set of crossing warps, means to move the crossing warps from one set of ground warps to the other set, a crossing warp advancer, a carrier therefor, a lock to hold the advancer and carrier normally forwardly with the advancer in front of the fells, a lay movable toward and from the fells, a controller on the lay normally in position to be inoperative with respect to the advancer and carrier, means operative on a given beat of the loom to place the controller in operative position during a single forward beat 40 of the lay, the latter thereupon becoming effective on said forward motion to unlock the carrier and also move the advancer laterally to a position at one side of the fell, means to move the carrier and advancer rearwardly during the 45 first part of the following rearward movement of the lay, other means to move the advancer to a position behind the crossing warps, means carried by the lay to have operative engagement with the carrier to move the latter and advancer to-

gether with the crossing warps forwardly on the next forward movement of the lay, the controller being in normal inoperative position, and means to thereupon render the lock operative to hold the carrier and advancer in forward position during 5 subsequent beats of the loom.

14. In a double shuttle loom operating with two sets of ground warps to form two ground sheds which meet at the fells of the latter and operating with a set of crossing warps, means to move the crossing warps from one set of ground warps to the other set, a crossing warp advancer, a carrier therefor, a lock to hold the carrier and advancer forwardly with the latter between and in front of the fells, a lay movable toward and from the fells, a controller on the lay normally in inoperative position, means operative on a single given beat of the loom to move said controller to operative position, the controller simultaneously unlocking said carrier and moving the 20 advancer laterally to a position at one side of the fells due to forward motion of the lay, means to move the unlocked carrier rearwardly as the lay moves backwardly, means to move the advancer into a position behind the crossing warps 25 when the carrier is rearward, means thereafter operative to move the controller to inoperative position before the next complete forward motion of the lay, and means on the lay operative 30 on said next forward beat of the lay to move the carrier forwardly into locking relation with respect to said lock to move the advancer and crossing warps forwardly to a position in front of the fells, said lock being effective to retain the carrier and advancer in forward position during 35 subsequent beats of the loom.

15. The method of weaving spaced webs connected by crossing warps, said method consisting in providing crossing warps and a system of warps for each web, crossing the crossing warps from each web to the other web at periodic intervals, advancing the point of crossing of the crossing warp threads to a position between the webs on a given beat of the loom to draw off crossing warps, and maintaining the crossing point of the crossing warps in said forward position independently of the webs for a succession of beats of the loom following said given beat.

ELBRIDGE R. HOLMES.
